NONROTATABLE HUB CAP

George D. Ball and Charles L. Tumulty,
Alexandria, Ind.

Application October 8, 1937, Serial No. 167,944

9 Claims. (Cl. 40—129)

This invention relates to a non-rotatable hub cap structure.

The chief object of this invention is to provide a hub cap structure which may be readily substituted for a standard, normally rotatable, hub cap and when substituted includes a normally non-rotatable cover arrangement which fully conceals all rotatable parts thereof and of the supporting hub as well.

10 The chief feature of the invention is the arrangement and construction of the device whereby the foregoing object is accomplished.

Other objects and features will appear more fully hereinafter.

15 The full nature of the invention will be understood from the accompanying drawing and the following description and claims:

In the drawing, Fig. 1 is a central sectional view 20 through one embodiment of the hub cap structure, including the invention.

Fig. 2 is a front view thereof.

In Fig. 1 of the drawing, there is illustrated a base plate 10 of dished formation having its peripheral edge 11 turned back and beaded as at 12. 25 Suitably secured to the inside of this plate as by welding or the like, is a sleeve portion 13, the projecting edge 14 of which is turned back to form a beaded arrangement 15. The parts thus described are substantially identical to parts of a standard hub cap structure, it being understood for the purpose of disclosing this invention, the plate 10 has covering the same an outer cover plate of suitable ornamental design, the same being rigidly secured to said base plate at its periphery by being crimped or curled around the beaded edge 12.

30 This standard hub cover cap is frictionally associated with the wheel hub structure through the sleeve portion 13. This is conventional practice and is merely set forth herein for an understanding of the invention, it being understood thereby that the mounting of the structure upon the wheel hub is through the portion 13 in the conventional manner and, therefore, the portion 35 13 and the supporting base 10 rotate with the wheel hub.

35 The present invention is arranged to utilize these standard portions but in place of having the cover plate before mentioned rigidly secured to the base plate 10, there is now provided a cover plate 40 16 which has its peripheral edge 17 turned inwardly as at 18 and masks but is disassociated from the edge 11—12 of the base plate. This cover structure may be suitably ornamented and have a 45 suitable central formation. Herein it is provided

with a central well portion 19. This well portion may be a continuation of the portion 16 or may be of a detachable insert character. It may be suitably ornamented.

A sleeve 20 includes near one end an exterior 5 groove 21 and the portion 19 or the portion 16, if desired, includes suitable anchoring means, herein shown in the form of clips 22 welded to the portion 19 and having the finger portions 22a seatable in the groove. Through this arrangement, the cover cap 16 is rigidly associated with the sleeve 20. Any other suitable connection may be provided, however. The reason for this type of connection is that the parts 10 and 13 together with the parts hereinafter to be described may be 10 fabricated in mass production for a large variety of vehicles and only the portion 16, as desired, 15 may be utilized.

The sleeve 20 is provided with two spaced internal grooves 23 and 24. Split locking rings 25 and 26, respectively, retain in the sleeve 20 against axial displacement, an anti-friction structure indicated generally by the numeral 27, the outer sleeve portion 28 of which is relatively rigid with the sleeve 20 and the inner sleeve portion 29 of 25 which is rotatable relative thereto by reason of the balls 30.

A spindle 31 having the head portion 32 extends through and bears against, respectively, the inner raceway portion 29. A spacing sleeve structure 33 30 bears against the opposite face of the inner raceway member 29 and serves as a spacer to position the race structure in predetermined position on the spindle 31 relative to the plate 10. The spacing sleeve or collar 33 may be enlarged laterally 35 as at 34 to provide a greater area in contact with the sheet metal base plate 10.

The base plate 10 is apertured as at 35 and the same registers with a threaded opening 36 in the spindle 31. A relatively large washer 37 is positioned on the opposite side of the base plate 10 and the cap screw 38 extends through the washer 37, the aperture 35 in the base plate 10, and is threaded into the threaded opening 36 of the spindle 31. This rigidly connects the spindle 45 structure to a base plate 10 and by reason of the spacing sleeve 33—34 and the head portion 32, the anti-friction structure is positively positioned with respect to the base plate in connection with axial displacement. Thus, the interior end of the 50 sleeve 20 is maintained out of contact with the base plate 10 so that the entire masking or cover structure has no contact with the base plate 10 and is relatively rotatably supported with respect thereto, it, of course, being understood that in op- 55

eration it is the base plate 10 which rotates and the cover plate 16 which remains stationary.

If the weight of the parts associated with and including the cover plate 16 is insufficient for gravity to maintain the same relatively stationary when the base plate 10 is rotated, due to what slight friction there be between the supporting members, there may be provided suitable counter-weighting means 40 and suitably secured to the interior of the cover plate structure, for example, as by means of the weld 41.

Thus, there is provided a structure, the cover plate of which completely masks the wheel hub in substantially the same manner as a standard hub cap does but it does not rotate.

It will be quite apparent, therefore, that basically this explanation of the present invention is common thereto and that the basic result thereof is complete masking of the hub structure and non-rotation of the hub cover plate.

While the invention has been described in great detail in the foregoing description and the drawing similarly illustrates the same, the aforesaid is by way of illustration only and is not restrictive in character. The several modifications which will readily suggest themselves to persons skilled in this art, are all considered within the broad scope of this invention, reference being had to the appended claims.

30 The invention claimed is:

1. A non-rotatable hub cap structure including in combination a main hub cap forming base with an interior hub anchorable sleeve and rotatable with a supporting wheel hub, an ornamental cover plate co-extensive with and substantially masking the base, a spindle secured to the base, and means rotatably supported by the spindle and secured to the cover plate whereby the latter remains stationary while the spindle is rotated by the wheel hub.

35 2. A device as defined by claim 1, characterized by the cover plate including, a curled peripheral edge enveloping but spaced from the peripheral edge of said base, and said means preventing axial separation whereby peripheral edge clearance is maintained.

40 3. A device as defined by claim 1, characterized by the addition of weight means operatively associated with the cover plate to resist rotation thereof.

45 4. A relatively stationary hub cap structure including in combination a cover plate, a sleeve operatively connected thereto, anti-friction means therein, a spindle therein, a main hub cap structure secured to the spindle and arranged for wheel hub anchorage, the sleeve having an exterior groove thereon, and means engageable in the exterior groove for detachably connecting the cover plate to the sleeve.

50 5. A relatively stationary hub cap structure including in combination a cover plate, a sleeve operatively connected thereto, anti-friction means therein, a spindle therein, a main hub cap structure secured to the spindle and arranged for

wheel hub anchorage, the sleeve including a pair of spaced internal grooves, and means therein located at opposite sides of the anti-friction means preventing axial displacement therebetween.

5 6. A relatively stationary hub cap structure including in combination a cover plate, a sleeve operatively connected thereto, anti-friction means therein, a spindle therein, a main hub cap structure secured to the spindle and arranged for wheel hub anchorage, the sleeve having an exterior groove thereon, means detachably connecting the cover plate to the sleeve, said sleeve also including a pair of spaced internal grooves, and means located in each internal groove and located at opposite sides of the anti-friction means and preventing axial displacement between the sleeve and anti-friction means.

10 7. A relatively stationary hub cap structure including in combination a cover plate, a sleeve operatively connected thereto, anti-friction means therein, a spindle therein, a main hub cap structure secured to the spindle and arranged for wheel hub anchorage, sleeve means about the spindle and laterally interposed between the anti-friction means and the hub cap structure for spacing the first mentioned sleeve therefrom, the first mentioned sleeve having an exterior groove thereon, and means engageable in the exterior groove for detachably connecting the cover plate to the sleeve.

15 8. A relatively stationary hub cap structure including in combination a cover plate, a sleeve operatively connected thereto, anti-friction means therein, a spindle therein, a main hub cap structure secured to the spindle and arranged for wheel hub anchorage, sleeve means about the spindle and laterally interposed between the anti-friction means and the hub cap structure for spacing the first mentioned sleeve therefrom, the sleeve including a pair of spaced internal grooves, and means therein located at opposite sides of the anti-friction means preventing axial displacement between the sleeve and anti-friction means.

20 9. A relatively stationary hub cap structure including in combination a cover plate, a sleeve operatively connected thereto, anti-friction means therein, a spindle therein, a main hub cap structure secured to the spindle and arranged for wheel hub anchorage, sleeve means about the spindle and laterally interposed between the anti-friction means and the hub cap structure for spacing the first mentioned sleeve therefrom, the first mentioned sleeve having an exterior groove thereon, means associated with the groove detachably connecting the cover plate to the sleeve, said first mentioned sleeve including a pair of spaced internal grooves, and means located in each and located at opposite sides of the anti-friction means preventing axial displacement between the sleeve and anti-friction means.
